UNITED STATES PATENT OFFICE.

WILLIAM A. KNOWLTON, OF ROCKFORD, ILLINOIS.

CULTIVATOR.

SPECIFICATION forming part of Letters Patent No. 358,557, dated March 1, 1887.

Application filed April 22, 1886. Serial No. 199,772. (No model.)

To all whom it may concern:

Be it known that I, WILLIAM A. KNOWLTON, a citizen of the United States, residing in the city of Rockford, in the county of Winnebago and State of Illinois, have invented new and useful Improvements in Cultivators, of which the following is a specification.

This invention relates to a class of cultivators known as the "straddle-row" cultivator.

10 The object of this invention is to regulate the running-depth of the shovels and hold them to their adjusted running-depth, to assist in lifting the shovel-beams and the shovels thereto attached, and to support them in their elevated position. To accomplish these objects and other features, all of which will be herein-after more fully described, I have designed and constructed the apparatus represented in the accompanying drawings, in which—

20 Figure 1 is a plan view of portions of a cultivator embodying my invention. Fig. 2 is a side elevation showing my improvements. Fig. 3 is a transverse vertical section on dotted line *a* on Fig. 2, and Fig. 4 is a transverse vertical section on dotted line *b* on Fig. 1.

25 The several parts represented in the figures of the drawings, consisting of the wheels 1, arching or crank-formed axle-tree 2, tongue-beams 3, shovel-beams 4, shovels 5, and handles 6, are substantially such as heretofore employed in like machines.

30 The shovel-beams are joined and supported in their relative position near their forward ends by a tubular stretcher, 7, and a screw-bolt passed through the beams and through the tubular stretcher to clamp and hold the beams in position against the ends of the stretcher. A tubular stretcher, 8, is placed between the rear portion of the beams, and a 35 screw-bolt is passed through the handle 6, through the beams 4, and tubular stretcher 8 and serves to clamp and hold the parts in their relative position. The stretcher 8 is provided with a spring-supporting arm, 9, extending 40 from its central position forward in a horizontal plane between the shovel-beams, and is provided with a series of transverse horizontal holes, for a purpose hereinafter to appear. The stretcher 8 is also formed with depending 45 end arms with lugs to embrace the under edge of the beams, to prevent the stretcher turning on its bolt-support.

An open-sided joint-clip, 10, embraces the horizontal end portions of the axle-tree, inside of the wheels, and this clip is provided centrally with rearward-projecting ears 11, formed on their opposite outsides with semi-spherical or conic-recessed bearings. 55

An intermediate joint-yoke, 12, to connect the shovel-beams with the axle-tree, is provided with forward-projecting ears 13, to over-span the rearward-projecting ears of the clip, and are bored to receive the tubular journals 14, employed to produce a hinge-connection of the yoke with the clip. The tubular journals 65 have their bearing ends formed to engage the recessed bearings in the ears of the joint-clip, and a screw-bolt, 15, passed through the axial center of the tubular bearings, serves to fix the clip to the axle-tree in a manner to permit its adjustment lengthwise thereon to vary the relative position of shovel-gangs and permit a lateral swinging movement of the yoke on its tubular journal-supports. The yoke is provided with rearward-projecting ears 16, 75 which receive the forward ends of the shovel-beams, and a joint-bolt, 17, passed through the parts, serves to connect the beams with the yoke in a free manner, to permit a vertical movement of the shovel ends of the beams. 80 The yoke is also provided with a horizontal arm, 18, projecting rearward, and a vertical arm, 19, rising from its rear end centrally between the shovel-beams.

The vertical arm 19 of the intermediate 85 joint-yoke is provided with a series of transverse holes. An endwise-compression spring, 20, in this instance produced from plate material in S form, is connected at its forward end to the vertical arm 19 of the intermediate 90 joint-yoke, and at its rear end to the horizontal spring-supporting arm 9 of the tubular stretcher 8. The spring 20 in its connection with the horizontal spring-supporting arm, by means of the series of holes formed therein, is 95 made adjustable lengthwise thereon to vary its spring-force, and in its connection with the vertical arm of the joint-yoke, by means of the series of holes formed therein, is made vertically adjustable, to vary its downward action to regulate the running depth of the shovels or its upward action to vary its lifting and holding force on the shovel-beams. This 100 action will be readily understood by an in-

spection of Fig. 2 of the drawings, in which the shovel-beam in its solid-line position is below the connection of the spring with the vertical arm of the joint-yoke, and consequently the spring action tends to depress the shovel ends of the beams and cause the shovels to run at a greater depth, and when the beams are raised above the connection of the spring with the vertical arm its spring action will tend to lift the shovel ends of the beam to support them in their elevated position, as represented in the dotted lines.

In the drawings I have represented but portions of one side of a straddle-row cultivator, 15 and the portions necessary to a complete machine, not duplicates of the parts shown and herein described, may be any of the varieties of such parts known and used for like purposes, capable of use in connection with my 20 improvements.

I claim as my invention—

1. The combination, with the axle-tree, of the joint-clip embracing the same and provided with rearwardly-extending and perforated ends, recessed on their upper and lower sides, a yoke having forwardly-extending perforated ears, tubular journals seated in said ears and having their inner ends bearing in the recessed parts of the clip ends, and a bolt 25 pivotally connecting said clip ends and yoke-ears to rigidly clamp the joint-clip against oscillation on the axle, substantially as set forth.

2. The combination, with the joint-yoke and 30 with the shovel-beams pivoted thereto, of a spring connecting the yoke and shovel-beams,

said spring connected at its forward end to the yoke rearward of its connections with the shovel-beams and at its rear end to the shovel-beams rearward of its connection with the yoke, 40 substantially as and for the purpose set forth.

3. The combination, with the joint-yoke and with the shovel-beams hinge-jointed to the yoke, of a spring connected with the yoke and the shovel-beams, said spring made vertically 45 adjustable in its connection with the yoke, substantially as and for the purpose set forth.

4. The combination, with the joint-yoke and with the shovel-beams hinge-jointed to the yoke, of a spring connected with the yoke and 50 with the shovel-beams, said spring made adjustable in its connection with the beams lengthwise thereof, substantially as and for the purpose set forth.

5. The combination, with the shovel-beams, 55 of a joint-yoke hinge-jointed to the beams, said yoke provided with a horizontal arm projecting rearward, and a vertical arm rising from its rear end, said vertical arm provided with a series of transverse holes, substantially 60 as and for the purpose set forth.

6. The combination, with the horizontal arm, of the stretcher-support to the shovel-beams, and with the vertical arm of the joint-yoke hinge-jointed to the beams, of a spring hinge-jointed to the horizontal and vertical arms, 65 said spring made adjustable in its connections, substantially as and for the purpose set forth.

WILLIAM A. KNOWLTON.
